INSECT EXTERMINATOR

Frank S. Richardson, 1007 Dillard St., Greensboro, N.C.

Filed Mar. 19, 1959, Ser. No. 55,062

Term of patent 14 years

(Cl. D31—3)

FIG. 1

FIG. 2

FIG. 3

Fig. 1 is a front and top perspective view of an insect exterminator embodying my new design;

Fig. 2 is a front elevational view thereof, the rear not shown being substantially like the front; and

Fig. 3 is a transverse cross-sectional view taken on line 3—3 of Fig. 2.

The electric cord is shown broken away in Fig. 1 and broken off in Figs. 2 and 3 to indicate indeterminate length.

What I claim is:

The ornamental design for an insect exterminator, as shown and described.
